UNITED STATES PATENT OFFICE.

FRANK HOLMSTROM, JR., OF CHICAGO, ILLINOIS, ASSIGNOR, BY MESNE ASSIGNMENTS,
TO CHARLES R. BENNETT, OF KANSAS CITY, MISSOURI.

TELEPHONE REPRODUCER.

Application filed November 3, 1917, Serial No. 200,218. Renewed September 22, 1921. Serial No. 502,511.

To all whom it may concern:

Be it known that I, FRANK HOLMSTROM, Jr., a citizen of the United States of America, and resident of Chicago, Cook County, Illinois, have invented certain new and useful Improvements in Telephone Reproducers, of which the following is a specification.

My invention relates to improvements in telephone reproducers.

10 Among the objects of my invention are the following:

To provide means in a device of the above character that will permit the use of a unitary microphone element removable and re-
15 placeable as a whole from and in relation to the receiving part of the device.

To produce means for properly securing the microphone element in juxtaposition to the receiving part.

20 To produce means in such a device, whereby all tension may be relieved from the diaphragm proper and such that after the element is secured in position tension may be applied to the diaphragm by adjusting
25 means.

To provide other details of improvement tending to increase the efficiency and serviceability of a reproducer of the above character.

30 The means for accomplishing the foregoing and other useful ends are hereinafter set forth and claimed.

Referring to the accompanying drawing Fig. 1 shows a side elevation of the instrument with a portion of the casing cut away and the microphone and its associated parts in cross section in a plane with the limbs of a magnet.

Figure 2 is a sectional view of the instrument looking in the direction indicated by the arrows along line A—B in Fig. 1 showing the method used in mounting the microphone cell.

As shown in the drawings this invention 45 comprises a magnet which responds to current changes to vibrate the diaphragm of a microphone cell. In Fig. 1. is shown a magnet having two steel limbs 3 and 4, which are clamped together at the lower end by a bolt 5, clamping between the limbs a piece of soft iron 6 of suitable thickness to keep them apart the proper distance. This piece of iron is extended through the lower end of the casing to form a lug by which said instrument may be mounted and is also held

to the casing by means of screws 7 to keep the magnet in a firm position in the casing. Near the upper end the two limbs are clamped together by a brass bolt 8 clamping a brass piece 9 and a soft iron pole piece 10 60 between said limbs. This bolt, furthermore, clamps a brass support 11 to the outer side of the limb 3 and a brass support 12 to the outer side of the limb 4. On the upper end of the pole piece 10 there is wound a magnetic coil 13 for operating its armature 14. This armature has one end resting up against an angle heel piece 15 which is secured to the member 11 in any suitable manner. The other end of the armature 14 is provided 65 with an elongated portion or pin to which a link 16 is connected. Through the upper end of the link 16 is a lever 17 which is supported at one end by a fulcrum on the end of the screw 18, which screw is in turn 70 mounted in a pivoted or tilting arm 19 which is adapted to be tilted about an axis 20 when the screw 21 is adjusted one way or another and which is held against the head of said screw 21 by means of a spiral spring 22. 75 The other end of the lever 17 is supported by a link 23 which is connected at the other end to the movable electrode and front diaphragm of a microphone cell. When the screw 21 is operated it raises or lowers the 80 fulcrum and thereby regulates the air gap between the armature 14 and the magnet 13, and when the screw 18 is operated it forces the lever 17 nearer to or further away from the link 16 thereby varying the leverage of 85 said lever so as to secure the desired leverage between the armature and the diaphragm in order to amplify the vibration of said armature when transmitted to the microphone. Mounted upon the end of the supports 11 and 12 is a plate 24, having a circular opening in the center thereof, and a bridge 25 which is insulated from the supports 11 and 13 by fibre washers and secured to the ends of supports 11 and 12 by means of suitable 90 studs and nuts. Slidably mounted in the bridge 25 is a microphone of well known type which forms a complete unit and comprises a cup 26 having a plug extension which is clamped into an opening in the 95 bridge 25, said cup having a back electrode mounted therein and having a cap 27 which clamps a mica diaphragm 28 between itself and said cap. The mica diaphragm carries a front or movable electrode and a stud to 100

105 110

which the link 23 is secured, the opening between said front and back electrodes being nearly filled with granular carbon in the usual manner. Securely fastened to the stud 5 of the mica diaphragm is a spring 29 which bridges across the opening in the plate 24 and the ends of which rest on a counterbored surface on the upper side of said plate, this spring tends, normally, to hold the microphone 10 phone cell up toward the bridge 25, and is used to maintain a certain tension toward the mica diaphragm when the cell is pressed toward the plate 24 and clamped by means of the set screw 30 (Fig. 2). It will be 15 understood that the magnetism of the permanent magnet comprising limbs 3 and 4 tends to draw the armature 14 toward the pole piece 10, but the tension of the spring 29 exerted on the lever 17 holds said armature at a slight distance from the said pole piece, according to the adjustment of the screw 21. Now when telephonic or other varying currents are passed through the magnet 13, the magnetism of the permanent 25 magnet is increased and decreased thereby and the armature 14 is vibrated. These vibrations will be transmitted to the diaphragm and front electrode of the microphone cell by means of the lever and link 30 arrangement and the amplitude of said vibrations will be somewhat increased by the action of said lever, so that when a circuit is connected through said cell and a current is passed therethrough, said current will be 35 fluctuated by the increasing and decreasing of the resistance of said cell in a well-known manner. Clamped one on either side of the limbs 3 and 4 are a pair of terminal blocks of insulating material only one of which is 40 shown at 31. The block 31 carries a pair of terminals 32 and 33, the terminal 33 being connected to one terminal of the magnet 13 and the terminal 32 being connected by means of the plate 24 with the front electrode 45 of the microphone cell. The other terminal block (not shown) also has a pair of terminals mounted thereon, one of which is connected to the other terminal of the magnet 13 and the other of which is connected by 50 means of the bridge 25 and cup 26 with the back electrode of said cell. Secured to the soft iron piece 6 by means of suitable screws is a cap 34 provided with a pair of bushed openings through which the wires 55 leading from the terminals 32, 33, etc. may be extended. A casing 35 entirely encloses said instrument and is fastened in the cap 34 by suitable screws.

It will therefore be seen that I have provided a very efficient form of telephone repeater or amplifier and one which is very easily repaired, the instrument being so designed that in order to repair or change the microphone cell only the bridge 25 need be 60 removed, after which the cell, which is as-

sembled as a unit, may be very easily removed.

What I claim as my invention is:

1. In a reproducer, a receiver element having an armature, a resilient element secured to oppose the magnetic pull of the receiver magnet armature to hold it way from the magnet polepiece, means for adjusting the opposing forces to regulate the distance between armature and polepiece, a microphone unit, means for linking the diaphragm of said unit to said element after the pull of the opposing forces is adjusted, and means for anchoring the back of the microphone after the adjustment. 70

2. In a reproducer, a receiver element having an armature, a resilient element secured to oppose the magnetic pull of the receiver magnet armature to hold it away from the magnet polepiece, means for adjusting the opposing forces to regulate the distance between armature and polepiece, a microphone unit, means for linking the diaphragm of said unit to said element after the pull of the opposing forces is adjusted, means for anchoring the back of the microphone after the adjustment, said last means including a bridge over the microphone secured to the magnet structure. 85

3. In a reproducer, a receiver element having an armature, a resilient element secured to oppose the magnet pull of the receiver magnet armature to hold it away from the magnet polepiece, means for adjusting the opposing forces to regulate the distance between armature and polepiece, a microphone unit, means for linking the diaphragm of said unit to said element after the pull of the opposing forces is adjusted, means for anchoring the back of the microphone after the adjustment, said last means including a bridge over the microphone, secured to the magnet structure, said bridge on the side of the resilient member away from the armature. 95

4. In a reproducer, a receiver element having an armature, a resilient element secured to oppose the magnet pull of the receiver magnet armature to hold it away from the magnet polepiece, means for adjusting the opposing forces to regulate the distance between armature and polepiece, a microphone unit, means for linking the diaphragm of said unit to said element after the pull of the opposing forces is adjusted, means for anchoring the back of the microphone after the adjustment, said last means including a bridge over the microphone, secured to the magnet structure, said bridge on the side of the resilient member, away from the armature, said force adjusting means located between the resilient member and the armature. 115

5. In a reproducer, a receiver having a magnet, an armature, an extension support, 120

attached to said magnet extending beyond said armature, a spring plate over said armature sustained by said extension, a connecting link from said armature to said spring serving to hold the armature away from the magnet polepiece, said spring balancing the magnetic pull, a microphone unit having its diaphragm secured to said spring on the side away from the armature, a bridge over said microphone having its ends anchored to said extension, a pin projecting from the back of said unit through an opening in said bridge and means for securing said pin to said bridge after the spring and magnetic pull are balanced.

6. In a reproducer, a receiver element having an armature, a resilient element secured to oppose the magnetic pull of the receiver magnet armature to hold it away from the magnet polepiece, means for adjusting the opposing forces to regulate the distance between armature and polepiece, a microphone unit, and means for anchoring the back of the microphone after the adjustment in a position free from any of the normal pull of the receiver magnet.

7. In a reproducer, a receiver element having an armature, a resilient element secured to oppose the magnetic pull of the receiver magnet armature to hold it away from the magnet polepiece, means for adjusting the opposing forces to regulate the distance between armature and polepiece, a microphone unit, means for anchoring the back of the microphone after the adjustment, said last means including a bridge over the microphone secured to the magnet structure in a position free from any of the normal pull of the receiver magnet.

8. In a reproducer, a receiver element having an armature, a resilient element secured to oppose the magnet pull of the receiver magnet armature to hold it away from

the magnet polepiece, means for adjusting the opposing forces to regulate the distance between armature and polepiece, a microphone unit, means for anchoring the back of the microphone after the adjustment, said last means including a bridge over the microphone secured to the magnet structure, said bridge on the side of the resilient member away from the armature in a position free from any of the normal pull of the receiver magnet.

9. In a reproducer, a receiver element having an armature, a resilient element secured to oppose the magnet pull of the receiver magnet armature to hold it away from the magnet polepiece, means for adjusting the opposing forces to regulate the distance between armature and polepiece, a microphone unit, means for anchoring the back of the microphone after the adjustment, said last means including a bridge over the microphone secured to the magnet structure, said bridge on the side of the resilient member away from the armature, said force adjusting means located between the resilient member and the armature in a position free from any of the normal pull of the receiver magnet.

10. In a reproducer, a permanent magnet receiver, a microphone unit and a resilient element, means for balancing the pull of the resilient element against the pull of the receiver magnet, and means for thereafter anchoring the microphone element and to render the same responsive to the receiver element while relieving the microphone element of any of the receiver magnet pull during the time that the receiver magnet is not responding to voice currents.

Signed by me at Chicago, Cook County, Illinois, this 19th day of October, 1917.

FRANK HOLMSTROM, JR.
